SNARE DRUM BRUSH OR SIMILAR ARTICLE

Alfred J. De Christopher II, 10072 Westwanda Drive,
Beverly Hills, Calif. 90210

Filed Jan. 25, 1971, Ser. No. 109,745

Term of patent 14 years

Int. Cl. D17—04

U.S. Cl. D56—1

FIG. 1 is a perspective view of a snare drum brush or similar article showing my new design;

FIG. 2 is a front elevational view;

FIG. 3 is a side elevational view;

FIG. 4 is a top plan view; and

FIG. 5 is a bottom plan view.

I claim:

The ornamental design for a snare drum brush or similar article, substantially as shown.
